Patented Oct. 21, 1975

237,243

PORTABLE, SELF-CONTAINED COOKING SET

John Erik Faldt, Vashy, Sweden, assignor to
AB Optimus, Vashy, Sweden

Filed Sept. 10, 1973, Ser. No. 395,414

Term of patent 14 years

Int. Cl. D7—02

U.S. Cl. D7—107

FIG. 2.

FIG. 3.

FIG. 5.

FIG. 6.FIG. 7.

FIG. 1 is an exploded perspective view of all elements of a portable, self-contained cooking set, showing my new design;

FIG. 2 is a perspective view thereof, shown in the assembled condition;

FIG. 3 is a side elevational view thereof, all sides thereof being identical thereto;

FIG. 4 is a top plan view of the stove portion of the portable, self-contained cooking set, shown with the cover removed;

FIG. 5 is a sectional view thereof, taken on lines 5—5 of FIG. 4;

FIG. 6 is a sectional view thereof, taken on lines 6—6 of FIG. 4;

FIG. 7 is a sectional view thereof taken on lines 7—7 of FIG. 4.

I claim:

The ornamental design for a portable, self-contained cooking set, as shown and described.
